(57) **CLAIM**

The ornamental design for headgear, as shown and described.

DESCRIPTION

FIG. 1 is an isometric view of headgear.

FIG. 2 is a first side elevation view of the headgear of FIG. 1.

FIG. 3 is a second side elevation view of the headgear of FIG. 1.

FIG. 4 is a first end elevation view of the headgear of FIG. 1.

FIG. 5 is a second end elevation view of the headgear of FIG. 1.

FIG. 6 is a top plan view of the headgear of FIG. 1.

FIG. 7 is a bottom plan view of the headgear of FIG. 1; and, FIG. 8 is an additional isometric view of the headgear of FIG. 1.

The features shown in broken lines in the drawing figures illustrate environmental structure and form no part of the claimed design.
